UNITED STATES PATENT OFFICE.

LOUIS BURGER, OF CHICAGO, ILLINOIS.

DESIGN FOR A SOUVENIR SPOON.

SPECIFICATION forming part of Design No. 22,319, dated April 4, 1893.

Application filed February 28, 1893. Serial No. 464,111. Term of patent 3½ years.

To all whom it may concern:

Be it known that I, LOUIS BURGER, a citizen of the United States, residing at Chicago, in the county of Cook and State of Illinois, have invented and produced a new and original Design for a Souvenir Spoon, of which the following is a description.

The drawing illustrates one face of a spoon embodying my design.

The leading feature of my design consists in the head or end portion in the form of a tapering panel upon which appears a representation of Queen Isabella, which panel terminates in a scroll outlined medallion upon which appears the representation of a crown. The remainder of the shank portion is given

the outline illustrated to represent Columbus holding a globe in one hand and standing upon a pedestal, from which pedestal the bowl extends. Between the representation of Columbus and the panel the shank is given a depressed and embossed scroll outline. At the head or end portion rays are represented as extending radially from the crown.

What I claim as new, and desire to secure by Letters Patent, is—

The design for a souvenir spoon substantially as shown and described.

LOUIS BURGER.

In presence of—

M. J. FROST,
W. N. WILLIAMS.
